UNITED STATES PATENT OFFICE.

HENRY IZARD, OF PORTLAND, OREGON.

LIQUID-FUEL BURNER.

1,074,435.

Specification of Letters Patent. Patented Sept. 30, 1913.

Application filed November 27, 1912. Serial No. 733,873.

To all whom it may concern:

Be it known that I, HENRY IZARD, a citizen of the United States, residing at Portland, in the county of Multnomah and State 5 of Oregon, have invented certain new and useful Improvements in Liquid-Fuel Burners; and I do declare the following to be a full, clear, and exact description of the invention, such as will enable others skilled 10 in the art to which it appertains to make and use the same.

This invention relates to liquid fuel burners, and more especially to such as have a perforated burner tube; and the object of 15 the same is to produce a device of this character capable of being placed within the firebox of an ordinary stove or range and supported therein on two standards rising from the grate.

20 This and other objects are accomplished by the construction hereinafter more fully described and claimed, and as shown in the drawings wherein—

Figure 1 is a side elevation of this improved burner, showing it disposed within a stove which latter is illustrated in section; Fig. 2 is an enlarged plan view of the burner complete. Fig. 3 is an end elevation of the burner shown in Fig. 2. Fig. 25 4 is a central longitudinal section on the line 4—4 of Fig. 2. Fig. 5 is a horizontal section on the line 5—5 of Fig. 4. Fig. 6 is a cross section on the line 6—6 of Fig. 2; and, Fig. 7 is a perspective detail to be 30 referred to hereinafter.

In the drawings let the letter S designate an ordinary stove mounted on legs L and having a grate G above its ash pit A and beneath its fire box F. The object of the 40 present invention is to place a burner within the fire box instead of heating the same by solid fuel, and to connect the burner with a source of liquid fuel supply—perhaps an elevated tank containing liquid fuel 45 such as gasoline, kerosene, or any proper distillate.

In the drawings the numeral 1 designates a feed pipe which is led, through a suitable controlling valve 2, to and through the side 50 of the stove at the point 3, to and through an expanding extension 4, and into one end of what might be called a heating tube 5 which is of larger diameter than the feed pipe 1. At its other or outer extremity 55 this tube 5 is connected through an elbow 6 with a cross pipe 7, and the latter through

a second elbow 8 with a second heating tube 9 parallel with and constructed like the first but spaced some little distance therefrom; and each of said elbows has a 60 reducing extension 15' in line with the axis of its tube. The opposite or inner end of the second tube 9 is connected, through a peculiar form of coupling best seen in Fig. 7, with a burner tube yet to be described. 65 This coupling comprises a tubular body 11 having internal threads 12 at its outer end to engage the extremity of the tube 9, a compound elbow 13 rising from said body with its outer end directed along a line 70 parallel with the line of said body but reduced and internally threaded as at 14, and a reducing extension 15 at the inner end of said body, having a nipple 16 projecting therefrom as best seen in Fig. 7. Screwed 75 into the threaded end 14 of the compound elbow 13 is a burner tube 17, herein shown as somewhat smaller than the heating tubes 5 and 9 but larger than the feed pipe 1, and the outer end of this tube is closed by a 80 cap 18 while its lower side is pierced with a number of jet openings 19, whereof only two are shown in Fig. 4.

The support for this device is extremely simple. It consists of two like standards 20, 85 each having a base 21 which may rest upon the grate G or be secured thereto, and a T-coupling 22 at its upper end, and into the head of the T are passed or secured the inner ends of two short sections 23 of rods. 90 At the inner end of the burner the outer extremity of one of these rod-sections carries a T-coupling 24 through which the feed-pipe 1 passes freely and uninterruptedly, whereas the other rod-section carries a T-coupling 95 25 whose head has one end connected by a proper nipple with the reducing extension 15, and its other end closed by a plug 26. At the outer end of the burner each rod-section 23 carries at its outer end a T-coupling 100 27 whose head has its inner end connected by a short nipple 28 (see dotted lines in Fig. 2) with the reduced outer end of one of the elbows above described, and its outer end closed by a plug 29. It follows from this 105 construction that the two standards 20 support the four rod-sections 23, and the latter at their outer extremities support both ends of the two heating tubes and the inner end of the feed pipe 1, while the heating tube 9 110 through its special form of coupling supports the tube 17 which stands above the

level of both heating tubes and above a line drawn about midway between them.

A plate 30 is disposed in a plane above said heating tubes and below the burner tube, its body being provided with large holes 31 standing respectively beneath the jet openings 19, and with a series of small perforations 32; and from the four corners of this plate project fingers 33 which extend 5 over and are bent down outside of the two heating tubes 5 and 9 as best seen in Fig. 6. These fingers preferably stand inside the corner elbows or couplings, and by them the plate is supported in such manner that it 10 may be removed for cleansing. Below the burner proper stands a pan 34, preferably having a single fork 35 at each extremity (see Fig. 5), and each standard carries a collar 36 rendered adjustable by means of a 15 set screw 37, with which collar said fork engages. Thereby is produced an adjustable pan for catching the drippings and for 20 starting the burner by the customary method of permitting a little free oil to drop therein 25 and igniting it with a match.

All parts are of course of metal, and exact details are unimportant.

The uses of a burner of this type are so well known that they hardly need repetition here. The liquid flowing in through the 30 feed pipe 1 passes through the heating tube 5 and then through the heating tube 9 and up the fixture shown in Fig. 7 into and throughout the length of the tube 17; mean- 35 while it has been heated within said tubes 5 and 9 by the burning gases which are jetted downward from the openings 19 through the holes 31 in the plate 30 and onto the pan, and by the latter deflected so that the heat 40 rises around both sides of both of the heating tubes 5 and 9 and converts the liquid fuel therein into vapor before it rises through the elbow 13 into the burner tube. While I have shown but two jet openings 19 45 in the latter, it is obvious that there could be a greater or perhaps a lesser number. The purpose of the perforations 32 in the plate 30 is to permit the heat which is flashed downward through the holes 31 50 onto the pan 34 to rise freely so that it may reach all parts of the interior of the firebox F, although a large portion of said heat rises past the edges of the plate 30 and comes into direct contact with the heating tubes 5 and 55 9. The obvious purpose of the plugs 26 and 29 and of the nipples connecting the T-couplings with the inner ends of the second heating tube 9 and both ends of the elbows 60 at the outer extremities of the heating tubes, 60 is in order that when such plugs are removed a suitable tool will be passed through the tubes for cleaning them out. If the accumulations become too large to be handled in this manner it is quite possible to remove 65 the T-couplings from the nipples, and with-

draw the latter from the reducing extensions 15' at the outer ends of the elbows 6 and 8 or the special form of coupling shown in Fig. 7; and thereafter a considerably larger tool may be inserted into and through these 70 couplings and considerably larger pieces of scale or other accumulations removed therefrom as will be clear.

What is claimed as new is:

1. A liquid fuel burner comprising a pair 75 of spaced heating tubes connected at one extremity, a feed pipe connected with the inner end of one of said tubes, and a burner tube standing above the space between said heating tubes and pierced with jet openings 80 in its lower side; combined with a coupling between the last-named heating tube and said burner tube, a plate having fingers at its corners bent outwardly and downwardly so as to overlie said heating tubes and its body 85 perforated and pierced with large holes under said jet openings, and a support for said burner.

2. In a liquid fuel burner, the combination with a horizontal feed pipe, a heating 90 tube connected at its inner end therewith, a second heating tube parallel with the first, elbows at the outer ends of said tubes connected by a cross pipe and each elbow having a reducing extension in line with the 95 axis of its tube, a coupling at the inner end of the second heating tube also having a reducing extension in line with its axis, a compound elbow rising from this coupling, and a burner tube carried by said elbow; of nipples in said reducing extensions, T-couplings 100 on said nipples, plugs in the outer ends of said couplings, and means for supporting such couplings.

3. In a liquid fuel burner, the combination with a horizontal feed pipe, a heating tube connected at its inner end therewith, a second heating tube parallel with the first, elbows at the outer ends of said tubes connected by a cross pipe and each elbow having a reducing extension in line with the axis of its tube, a coupling at the inner end of the second heating tube also having a reducing extension in line with its axis, a compound elbow rising from this coupling, and a burner tube carried by said elbow; of nipples in said reducing extensions, T-couplings 110 engaging said nipples, plugs closing the outer ends of said couplings, a T-coupling loosely inclosing the feed pipe, cross rods 115 connecting said couplings in pairs at the ends of the burner, and supports for said rods.

4. In a liquid fuel burner, the combination with a horizontal feed pipe, a heating 125 tube connected at its inner end therewith, a second heating tube parallel with the first, elbows at the outer ends of said tubes connected by a cross pipe and each elbow having a reducing extension in line with the 130

axis of its tube, a coupling at the inner end of the second heating tube also having a reducing extension in line with its axis, a compound elbow rising from this coupling, 5 and a burner tube carried by said elbow, of nipples in said reducing extensions, T-couplings engaging said nipples, plugs closing the outer ends of said couplings, a T-coupling loosely inclosing the feed pipe, cross rods connecting said couplings in pairs at the ends of the burner, upright standards connected at their upper ends with said rods, collars adjustably mounted on said standards, and a pan disposed beneath the burner 10 15 and having forks at its extremities loosely engaging the standards above their collars.

5. In a liquid fuel burner, the combination with a horizontal feed pipe, a heating tube connected at its inner end therewith, a second heating tube parallel with the first, 20 elbows at the outer ends of said tubes connected by a cross pipe and each elbow hav-

ing a reducing extension in line with the axis of its tube, a coupling at the inner end of the second heating tube also having a reducing extension in line with its axis, and a burner tube carried by said coupling; of nipples in said reducing extensions, T-couplings the inner ends of whose heads engage said nipples, plugs closing the outer ends of said 25 heads, a T-coupling whose head loosely incloses the feed pipe, cross rods connecting the shanks of said couplings in pairs at the ends of the burner, and upright standards having T-couplings at their upper ends em- 30 35 bracing said rods.

In testimony whereof I have hereunto set my hand in presence of two subscribing witnesses.

HENRY IZARD.
